HAIR WAVING DEVICE

Hedwik Marie Wells, Rossland, British Columbia,
CanadaApplication May 23, 1933, Serial No. 672,472
Renewed July 2, 1934

9 Claims. (Cl. 132—36)

The invention relates to a hair waving device and more especially to a device for simplifying the art of permanent waving, either marcel or finger wave characteristic.

5 The primary object of the invention is the provision of a device of this character, wherein a permanent wave may be had by the winding of the hair reversely around curling drums or cylinders, these being susceptible of expansion to straighten the coils and to stretch the same so that by the treatment of the hair in this condition, when subjected to moisture and heat, the same will be permanently waved in an expeditious manner, the device in its entirety being of novel 10 construction.

Another object of the invention is the provision of a device of this character wherein not only can the permanent waving of the hair be had but also the formation of ringlets at the ends of the 15 hair, these ringlets being formed in a novel manner.

A further object of the invention is the provision of a device of this character wherein the capacity thereof is such as to enable minimum 20 and maximum strands of hair to be waved in a single operation and in the waving operation the hair will be sustained stretched and smooth, while the ringlets at the ends of the strands of hair can be effected for permanency thereof.

30 A still further object of the invention is the provision of a device of this character which is extremely simple in construction, readily and easily operated, thoroughly reliable and efficient in its purposes, strong, durable, assuring the permanent waving of the hair and the formation of ringlets with dispatch and without inconvenience to a person operated upon for this purpose, and also inexpensive to manufacture.

35 A still further object of the invention is the provision of a device of this character wherein hair cannot only be permanently waved but simultaneously therewith a ringlet end to the hair can be had and the hair does not have to be set when subsequently shampooed to the waving thereof.

40 With these and other objects in view, the invention consists in the features of construction, combination and arrangement of parts as will be hereinafter more fully described in detail, illustrated in the accompanying drawings, which 45 disclose the preferred embodiment of the invention, and pointed out in the claims hereunto appended.

In the accompanying drawings:

50 Figure 1 is a top plan view of a device constructed in accordance with the invention show-

ing hair being treated thereby for the waving of the same and the formation of ringlets.

Figure 2 is an end elevation.

Figure 3 is a view similar to Figure 2 looking toward the opposite end of the device.

Figure 4 is a sectional view on the line 4—4 of Figure 1 looking in the direction of the arrows.

Figure 5 is a perspective view of the twin curling drums or cylinders of the device.

Figure 6 is a perspective view of a spreader 10 key for such drums or cylinders.

Figure 7 is a perspective view of a modified form of spreader key.

Figure 8 is a perspective view of the ringlet forming element of the device.

Figure 9 is a side elevation of a modified form thereof.

Figure 10 is a perspective view of a combined cover and clamp for the curler drums or cylinders.

Figure 11 is a plan view of the scalp protective unit of the device, showing by full lines the hair gripping section thereof closed and by dotted lines partly open.

Figure 12 is an enlarged fragmentary sectional view on the line 12—12 of Figure 11.

Similar reference characters indicate corresponding parts throughout the several views in the drawings.

Referring to the drawings in detail, the device 30 comprises a pair of spaced parallel curling drums or cylinders 10 preferably made from sheet metal having formed at opposite ends segmental oppositely disposed flanges 11, these at one end of said drums or cylinders being provided with slots 12 accommodating coupling studs 13 of connector rods 14. Thus it will be seen that the cylinders in their twin connection can be expanded from their normal condition. Each cylinder is longitudinally split at its inner side to provide a spreading gap 15 and in this manner the said drums or cylinders 10 are susceptible of expansion in a manner presently described.

Insertable in the gaps 15 in the drums or cylinders 10 is a double prong spreader key 20 which causes these drums or cylinders to expand from normalcy for the stretching of the strands of hair 21 reversely trained exteriorly about said drums or cylinders and in this fashion causing a stretching of the strands of hair 21 when wound about the drums or cylinders in the manner stated.

Insertable in the socket 19 is a ringlet forming unit 22 having a knurled circular plug end 23 and a finger knob turning end 24 respectively. In this instance the unit 22 between the plug end 55

23 and knob end 24 is outwardly tapered and this constitutes the ringlet forming area of said unit.

Arranged within the ringlet forming unit 22 is an electric heating unit 25 having the coupling socket terminal 26 and the prong connector terminal 27 respectively. The socket terminal 26 receives the prong terminal 18 when the plug end 23 is inserted in the socket 19 and by this connection the said unit 22 can be readily turned in the socket so that the ends of the strands of hair 21 can be coiled upon this unit 22 for the formation of ringlets 28, it being understood of course that the extremities of the hair will be tied by a cord or the like 29 at the outer end portion of said unit to enable the tight curling or ringlet formation to the hair on the manipulation of the unit 22 by engaging the knob 24 and turning the same by hand. The other prong terminal 18 and said prong terminal 27 are adapted for connection with an electric circuit through suitable separable couplings (not shown) and in association with the heating units may be a rheostat to control the heat qualities thereof.

25 One prong of the spreader key 20 carries a nib 30 which engages with the knurled plug end 23 to lock or hold the unit 22 against turning movement on the insertion of the key in the gaps 15 of the drums or cylinders 10 as should be obvious and this unit thus locked will prevent the ringlets from unwinding on the unit 22 as should be apparent.

Adapted to be fitted over the drums or cylinders 10 after the hair 21 has been curled reversely about these drums or cylinders is a combined cover and clamp including the intermediate crown 31 and opposite cylindrical portions 32, these encircling the said drums or cylinders 10 and this crown 31 has fitted therein tensioning springs 32 effective for drawing the cylindrical portions 32 toward each other, these portions being to some extent inherently resilient and in this manner they will exert a pressure upon the curled hair 21 on the drums or cylinders 10 to smooth and press the same in the operation of permanently waving the hair.

For use with the device is a scalp protective unit which includes a board 34, preferably of the shape shown in Figure 11 of the drawings, and said board is cut to provide a swinging clamping section 35 hinged at 36 to said board, the abutting edges 37 and 38 of the board and section being provided with a groove 39 and tongue 40 forming joint for permitting a tight grip to be had upon the hair 21 when trained between the board 34 and its swinging section 35. This protective unit in the use thereof is located close to the head of a person who is to have the operation for the permanent waving of the hair and such unit, including the board 34 and its section 35, carries a fabric pad 41, preferably made from felt, for contact with the scalp of the person as in the use of the board the pad 41 is located next to the scalp of such person. The swinging section 35 of the board 34 carries a latch 42 to engage a keeper 43 formed in the board 34 so as to permit this section 35 to be held in the full line position shown in Figure 11 of the drawings when gripping the hair as shown in Figures 2 and 3 of the drawings.

In Figure 7 of the drawings there is shown a slight modification of spreader key which includes a straight member 44 having the nib 45 and this member 44 is designed for connection in either gap 15 of the respective drums or cylinders

10 alike to the prongs of the spreader key 20. It is preferable to have the opposite edges of the prongs 20 and the member 44 provided with a groove 46 to constitute a seat for the edges of the drums or cylinders 10 at the gaps 15 therein for the interfitting of the spreader keys with these drums or cylinders.

In Figure 9 there is shown a slight modification of ringlet forming unit which includes the knurled plug end 47 and knob end 48 and also the intermediate straight circular portion 49 which is the ringlet forming area of said unit, the latter functioning alike to the unit 22 hereinbefore described.

In the operation of the device it is understood of course that the hair of a person to be operated upon for the permanent waving thereof may be treated for the moistening thereof either by a chemical solution, water or other liquid applicable under preliminary treatments for hair waving and thereafter a determined quantity of strands of the hair 21 is gripped by the board 34 through the instrumentality of its swinging section 35, this board being located next to the scalp of the person, thence the hair is reversely wound about the curling drums or cylinders 10. Thereafter the combined cover and clamping unit is mounted upon these drums or cylinders as shown in Figures 1, 2, 3 and 4 of the drawings. Then the ringlet forming unit is inserted in the socket 19 and the ends of the strands of hair are coiled thereabout and extremities made secure by the tie 29. Whereupon, this unit will be turned by hand, which stretches the hair at the wrappings about the drums or cylinders and also curls the same about said unit. Thereafter the spreader key 35 is inserted in the gaps 15 or in one of the same in the drums or cylinders or drum or cylinder 10 to cause the same to expand, thus tightening the strands of hair wrapped about the drums or cylinders 10 and the ringlet forming unit, while the cover and clamp will press the strands smooth and orderly. On exciting the heating elements of the device the permanent wave will be effected by the device. It will also be noted that the combined cover and clamp retains the moisture for the steaming of the hair in the operation of permanently waving the same.

From the foregoing it will appear that the hair will be not only permanently waved, either marcelled or finger waving thereof, but also ringlets at the ends of the strands of hair will be produced.

What is claimed is:

1. A device of the character described comprising a pair of spaced adjustably connected expandable curling cylinders, heating units within these cylinders, a combined cover and clamp encircling the cylinders, means insertable in each cylinder for the expanding thereof, a ringlet forming heating unit engageable with one of the heating units in the cylinders, and means for coupling the heating units with a heat producing source.

2. A device of the character described comprising a pair of spaced adjustably connected expandable curling cylinders, heating units within these cylinders, a combined cover and clamp encircling the cylinders, means insertable in each cylinder for the expanding thereof, a ringlet forming heating unit engageable with one of the heating units in the cylinders, means for coupling the heating units with a heat producing source, and means for effecting pressure from the combined cover and clamp about said cylinders.

3. A device of the character described comprising a pair of spaced adjustably connected expandable curling cylinders, heating units within

these cylinders, a combined cover and clamp enclosing the cylinders, means insertable in each cylinder for the expanding thereof, a ringlet forming heating unit engageable with one of the heating units in the cylinders, means for coupling the heating units with a heat producing source, means for effecting pressure from the combined cover and clamp about said cylinders, and a scalp protective board cooperative with the device.

5 4. A device of the character described comprising a pair of spaced adjustably connected expandable curling cylinders, heating units within these cylinders, a combined cover and clamp enclosing the cylinders, means insertable in each cylinder for the expanding thereof, a ringlet forming heating unit engageable with one of the heating units in the cylinders, means for coupling the heating units with a heat producing source, means for effecting pressure from the combined

10 cover and clamp about said cylinders, a scalp protective board cooperative with the device, and means related to the board for gripping hair therewith.

15 5. A device of the character described comprising a pair of spaced adjustably connected expandable curling cylinders, heating units within these cylinders, a combined cover and clamp enclosing the cylinders, means insertable in each cylinder for the expanding thereof, a ringlet forming heating unit engageable with one of the heating units in the cylinders, means for coupling the heating units with a heat producing source, means for effecting pressure from the combined

20 cover and clamp about said cylinders, a scalp protective board cooperative with the device, and means related to the board for gripping hair therewith.

25 6. A device of the character described comprising a pair of spaced adjustably connected expandable curling cylinders, heating units within these cylinders, a combined cover and clamp enclosing the cylinders, means insertable in each cylinder for the expanding thereof, a ringlet forming heating unit engageable with one of the heating units in the cylinders, means for coupling the heating units with a heat producing source, means for effecting pressure from the combined cover and clamp about said cylinders, a scalp protective board cooperative with the device, means related to the board for gripping hair therewith, means for manually turning the ringlet forming unit, and means for locking said unit against turning movement.

30 7. A device of the character described comprising expandable hair curlers disposed side by side, and a split resilient clamp embracing said curlers.

35 8. A device of the character described comprising expandable hair curlers disposed side by side, a split resilient clamp embracing said curlers, and a spreader for the curlers to expand the same.

9. A device of the character described comprising expandable hair curlers disposed side by side, a split resilient clamp embracing said curlers, a spreader for the curlers to expand the same, and heating units connected with said curlers.
